UNITED STATES PATENT OFFICE.

HARDES M. COLBYSON AND ABRAHAM S. DWORSKY, OF MINNEAPOLIS, MINNESOTA.

MACHINE FOR CLEANING MOTION-PICTURE FILMS.

1,230,120.

Specification of Letters Patent. Patented June 19, 1917.

Application filed March 20, 1916. Serial No. 85,266.

To all whom it may concern:

Be it known that we, HARDES M. COLBYSON and ABRAHAM S. DWORSKY, citizens of the United States, residing at Minneapolis, 5 in the county of Hennepin and State of Minnesota, have invented certain new and useful Improvements in Machines for Cleaning Motion-Picture Films; and we do hereby declare the following to be a full, clear, 10 and exact description of the invention, such as will enable others skilled in the art to which it appertains to make and use the same.

Our invention has for its object to provide 15 an extremely simple and highly efficient machine for cleaning motion picture films; and to such ends, generally stated, the invention consists of the novel devices and combinations of devices hereinafter described and defined in the claim.

In the accompanying drawings which illustrate the invention, like characters indicate like parts throughout the several views.

Referring to the drawings:

25 Figure 1 is a plan view of the machine with the first section removed;

Fig. 2 is a side elevation of the machine with the film receiving reels removed;

Fig. 3 is a side elevation of the film receiving reels and driving mechanism therefor;

Fig. 4 is an elevation showing mechanism found at the left of the line marked α^4 α^4 of Fig. 1; and

35 Fig. 5 is an elevation of the machine looking at the same from the left toward the right, in respect to Fig. 1.

In Figs. 2 to 5, inclusive, the floor on which the machine is supported is indicated 40 by the numeral 1. The numerals 2, 3, 4, 5 and 6 indicate bed plates secured on the floor in horizontal alinement. Rigidly secured on the bed plate 2 are bearing pedestals 7 and 8; rigidly secured on the bearing

45 pedestal 3 is a large central bearing pedestal 9 having a heavy transverse top plate 10; rigidly secured on the bed plate 4 are bearing pedestals 11 and 12; and rigidly secured on the bed plate 5 are bearing pedestals 13. Also, rigidly secured on the bed

plate 3 at front and rear of the pedestal 9 are short bearing pedestals 14 and 15. Journaled in the pedestals 7, 8, 11, 12, 13, 14 and 15, respectively, are transverse shafts 16, 17, 18, 19, 20 and 21. The present machine is 55 arranged to simultaneously clean four films, and hence, each of said shafts just noted carries four soft faced buffing wheels 22, of any well known or approved construction suitable for removing smoke, dirt and grease 60 without scratching the film surface.

For coöperation with each pair of buffing wheels 22, there is a grooved platen wheel 23. The four wheels 23 of the first set, at the left in respect to Fig. 2, are independently journaled to cross-heads 24; the four wheels of the second or intermediate set of wheels 23 are independently journaled to cross-heads 25; and the four wheels of the last or third set of platen wheels 23 are independently journaled to cross-heads 26. The cross heads 24 and 26 are supported in like manner and each is mounted for vertical sliding movements in upright cross-head guides 27, the bases of which, in turn, 75 have horizontal dove-tailed engagement with guide blocks 28 rigidly secured on the respective bed plates 2 and 4. The said cross-heads 24 and 26 are arranged for independent vertical adjustment, by manipulation of adjusting screw rods 29 swiveled to the caps of the cross-head guides 27 and having screw-threaded engagement with said cross-heads; and the said cross-head guides 27 are adapted to be given horizontal 80 adjustments longitudinally of the machine, by adjusting screw rods 30 swiveled to lugs on the respective bed plates 2 and 4 and having threaded engagement with base portions of said cross-head guides.

The intermediate cross-heads 25 are mounted for vertical sliding movements in cross-head guides 31, which, at their upper ends, have dove-tailed sliding engagement with horizontal guides 32 on the cross bar 95 10 of the pedestal 9. The said cross-heads 25 are adapted to be given independent vertical adjustments by screw rods 33 swiveled to the bottom plates of the respective cross-head guides 31 and having threaded engage- 100

ment with the said cross-heads; and the said cross-head guides 31 are adapted to be given independent horizontal adjustments longitudinally of the machine, by screw rods 34 5 swiveled to lugs on the cross bar 10 and having threaded engagement with the said cross-head guides 31.

By means described, the so-called platen wheels 23 are adapted to be given both vertical and horizontal adjustments toward and from the coöperating pairs of buffing wheels 22, and thus may be set in the proper pressure of the buffing wheels on the film, regardless of varying diameter of the said 15 buffing wheels. It will be understood that the buffing wheels will wear away quite rapidly in use, so that frequent adjustments of the above character will be required.

The films indicated by the character *y* are 20 adapted to be passed alternately over and under small idle guide wheels 35 arranged to coöperate in pairs with the platen wheels 23. The line of travel of the films over and under the coöperating wheels is indicated 25 in Fig. 2, by reference to which it will be seen, that the film passes, first over the first platen wheel 23 and under the two coöperating guiding wheels 35 and two coöperating buffing wheels 22; second, under the second 30 platen wheel 23 and over the two coöperating guide wheels 35 and two coöperating buffing wheels 22; and third, over the third platen wheel and under the two last coöperating guide wheels 35 and two last coöperating buffing wheels 22. Under this line 35 of travel it is obvious that the film will be buffed and cleaned, first on one side and then on the other, by the action of the alternated buffing wheels.

40 The idle guide wheels 35 above described may be supported in various different ways, but as shown, those that coöperate with the first and third buffing wheels are independently journaled on cross shafts or spindles 45 36 supported by the pedestals 7, 8, 11 and 12, while the guide wheels 35 that coöperate with the central buffing wheels are independently journaled on shafts or spindles 37 held by brackets 38, which, in turn, are 50 supported from the central pedestal 9.

From the last platen wheel 23 and coöperating guide wheel 35, the films pass between coöperating upper and lower feed rollers 39 and 40, which rollers are preferably 55 rubber-faced. The lower rollers 40 are carried by a transverse shaft 41 journaled in suitable bearings in the pedestals 13. The upper rollers 39 are journaled in bearings 42 adjustably mounted in the pedestals 13 60 and subject to adjusting screws 43, by means of which the tension of the coöperating rollers on the film may be varied at will.

At its central portion, the shaft 41 is provided with a pulley 44 over which a power-driven belt may be run to impart predetermined desired feeding movement to the film. The shafts 16, 17, 18, 19, 20, and 21, at their central portions, are provided with pulleys 45 over which power driven belts, not shown, are adapted to be run to impart rotation to 70 the said buffing wheels. Here it may be noted that the feed rollers 39 and 40 are rotated in a direction to cause the film to travel from the left toward the right, in respect to Fig. 2, and that the buffing wheels are preferably 75 all driven in a direction which tends to facilitate or assist in this movement of the film, although this latter feature is not highly important, because the speed of rotation of the said feed rollers determines the 80 speed of travel of the films.

From the feed rollers, the clean film passes to the film receiving reels 46 which are of the usual construction. These reels 46 are detachably secured to the ends of short 85 shafts 47 mounted in the upper ends of bearing posts 48, the lower ends of which fit sockets on the bed plate 6 and are rigidly but detachably held thereto by set screws 49. At their projecting ends, the shafts 47 90 are provided with grooved pulleys 50 that align with similar grooved pulleys 51 carried by the feed roller shaft 41. Transversely crossed guide belts 52 run over the aligned pulleys 50 and 51. The pulleys 50 and 51 95 are driven at such speed and are so arranged that the film will be wound onto the reel as fast as it comes from the feed rollers, even when the rolled part of the film is of the least diameter; and, as the size of the roll 100 increases, the belt 52 will simply be caused to slip. This arrangement keeps the films tightly wound on the reels and is a highly important feature.

It is a well known fact that in usage, motion picture films not only get dirty, but become scratched, and that the dirt accumulates in these scratches, producing on the motion picture flickering lines giving much the effect of rain. Films run through the machine described will be thoroughly cleaned and polished, and furthermore, the action of the buffing tool will not only clean the dirt out of the scratched lines, but will tend to close the scratches by a sort of a burnishing operation. The machine described is, as stated, arranged to simultaneously clean four films. This number may, as is obvious, be varied, either by way of increase or decrease.

By adjustments of the wheels 23, in respect to the buffing wheels 22, the frictional engagement between the buffing wheels and film may be varied. This frictional contact

should be such as to produce enough heat and horizontally toward and from the co-
to soften slightly the surface of the film and operating buffing wheels.
cause scratches therein to be filled or In testimony whereof we affix our signa-
smoothed over by the buffing and cleaning tures in presence of two witnesses.
5 action.

What we claim is:

In a film cleaning machine, the combina-
tion with a platen roller and a pair of co-
operating buffing wheels, of means for ad-
10 justing said platen roller, both vertically
